UNITED STATES PATENT OFFICE.

CLARENCE E. FRANKLIN, OF FOSTORIA, OHIO, ASSIGNOR OF ONE-THIRD TO JOHN W. McDONEL AND ONE-THIRD TO EARL K. CUNNINGHAM, BOTH OF FOSTORIA, OHIO.

RAILWAY-TORPEDO.

1,383,614.

Specification of Letters Patent. Patented July 5, 1921.

Application filed April 26, 1921. Serial No. 464,621.

To all whom it may concern:

Be it known that I, CLARENCE E. FRANKLIN, a citizen of the United States, residing at Fostoria, in the county of Hancock and 5 State of Ohio, have invented a new and useful Railway-Torpedo, of which the following is a specification.

This invention relates to railway torpedoes, one of its objects being to provide a 10 device of this character formed of but three pieces, and comprising an inner sealed waterproof case containing the detonating charge, an outer or supplemental sealed waterproof casing and the attaching metal strap which 15 is held to the torpedo by said outer casing.

A further object is to provide a structure 20 of this character which is cheap to manufacture, the two casings being made of paper properly waterproofed and sealed by crimping.

A further object is to provide a railway 25 torpedo including inner and outer casings whereby the detonating charge is doubly protected from moisture and whereby, should 30 the outer case become torn or mutilated in any manner, the charge will still be kept in condition to be exploded.

With the foregoing and other objects in 35 view which will appear as the description proceeds, the invention resides in the combination and arrangement of parts and in the details of construction hereinafter described and claimed, it being understood that, within the scope of what is claimed, 40 changes in the precise embodiment of the invention shown can be made without departing from the spirit of the invention.

In the accompanying drawings the preferred form of the invention has been shown.

40 In said drawings—

Figure 1 is a plan view of the torpedo, the free end portions of the attaching strap being removed.

Fig. 2 is a side elevation thereof.

45 Fig. 3 is an end elevation, the attaching strap being shown in section.

Fig. 4 is an enlarged section on line 4—4, Fig. 1.

Fig. 5 is a plan view of the outer casing 50 prior to being assembled with the other parts.

Fig. 6 is an end view of the outer casing.

Fig. 7 is a plan view of the inner casing prior to being assembled with the other 55 parts.

Fig. 8 is an end view thereof.

Referring to the figures by characters of reference 1 designates a section of flat paper tubing, the length thereof being substantially equal to the width, this section of tubing forming the inner casing of the torpedo and being designed to hold the detonating charge indicated by dotted lines at 2. The outer casing of the torpedo is also made of a section of flat paper tubing as shown at 3, the length of this tubing being substantially equal to the width and the said tubing 3 being so proportioned as to receive the portion 1 with the charge therein. Before said portion 1 is placed in the casing 3 the open 70 ends thereof are fastened together by crimping in any suitable waterproof manner and the inner casing 1 is then inserted into the outer casing 3 with the crimped ends of the casing 1 against the sides of the casing 3. A metal attaching strap 4 is then inserted through the casing 3 between said casing and the bottom of the casing 1 after which the open ends of the casing 3 are fastened together in a waterproof manner 75 by crimping or the like and as shown in detail in Fig. 4. As both of the casings are waterproof and sealed it will be obvious that the two casings afford double protection to the charge 2 from moisture and even 80 though the outer casing should become torn or mutilated the charge 2 would still be protected by the inner casing.

By means of the band 4 the torpedo can 85 be secured in the usual manner onto a rail.

It will be obvious that the torpedo can 90 be cheaply manufactured it merely being necessary to cut off proper lengths from paper tubes of different sizes so as thus to form the inner and outer casings 1 and 3 95 after which the parts can be quickly assembled as heretofore explained.

What is claimed is:—

1. A railway torpedo including a flat tube 100 constituting an outer casing, a flat tube constituting an inner casing and arranged within and extending transversely of the outer casing, an explosive charge within the inner casing, the ends of the inner and outer casings being sealed, and an attaching strap 105 extending between the inner and outer casings and projecting therebeyond.

2. A railway torpedo comprising flat paper tubes substantially square, an explosive charge contained within one of these tubes, 110

said tube being housed within the other tube with its ends against the sides of the outer tube, the ends of both tubes being sealed in a waterproof manner, and an attaching band 5 extending between the tubes and laterally therebeyond.

3. A railway torpedo comprising inner and outer flat paper tubes, the inner tube having its ends positioned parallel with the 10 sides of the outer tube, an explosive charge contained within the tube, each of said tubes

having its ends sealed to exclude moisture, and an attaching band extending between the tubes and beyond the ends of the outer tube. 15

In testimony that I claim the foregoing as my own, I have hereto affixed by signature in the presence of two witnesses.

CLARENCE E. FRANKLIN.

Witnesses:

E. K. CUNNINGHAM,
R. C. GUERNSEY.
